UNITED STATES PATENT OFFICE.

SCOTT NICHOLAS REGER, OF MORGANTOWN, WEST VIRGINIA.

DESIGN FOR AN AUTOMOBILE BODY.

Application filed April 8, 1929. Serial No. 30,805. Term of patent 7 years.

To all whom it may concern:

Be it known that, I, Scott N. REGER, a citizen of the United States, residing at Morgantown, in the county of Monongalia and State of West Virginia, have invented a new, original, and ornamental Design for an Automobile Body, of which the following is a specification, reference being had to the accompanying drawing, forming part thereof.

I claim:

The ornamental design for an automobile body, as shown.

SCOTT NICHOLAS REGER.
